UNITED STATES PATENT OFFICE.

CHARLES E. SCRIBNER, OF CHICAGO, ILLINOIS, ASSIGNOR TO WESTERN ELECTRIC COMPANY, OF CHICAGO, ILLINOIS, A CORPORATION OF ILLINOIS.

APPARATUS FOR TELEPHONE-SWITCHBOARDS.

SPECIFICATION forming part of Letters Patent No. 761,852, dated June 7, 1904.

Application filed August 17, 1895. Serial No. 559,628. (No model.)

To all whom it may concern:

Be it known that I, CHARLES E. SCRIBNER, a citizen of the United States, residing at Chicago, in the county of Cook and State of Illinois, have invented a certain new and useful Improvement in Apparatus for Telephone-Switchboards, of which the following is a full, clear, concise, and exact description, reference being had to the accompanying drawings, forming a part of this specification.

My invention is a device for use in a telephone-switchboard for transmitting signaling or calling currents from the central station to the substation.

It consists in a secondary source of current adapted to operate the substation call-bell included in the circuit of the line at the central office, a calling-key associated with the plug-circuit, and a device in a local circuit controlled by said calling-key for rendering the secondary source of calling-current active to transmit calling-currents over the line.

In the preferred form of my invention I provide a repeating-coil or transformer in association with the telephone-line at the central office, one of the helices of said transformer being included in the line-circuit and the other in a local circuit established by registering contacts of the plug and spring-jack, which local circuit may be temporarily completed by the calling-key through a generator of alternating or pulsatory currents.

My invention is particularly useful in connection with telephone-circuits which are permanently closed at the central station. In lines with such circuit connections, particularly if the instruments at the central station be of low resistance, a large proportion of the signaling-current may be diverted from the telephone-line through these instruments, and the operation of the substation-bell may be interfered with or prevented. In such cases my invention contemplates the inclusion of one helix of the transformer serially in the line-circuit and the provision of a separate local circuit including the other helix, into which the source of signaling-current may be introduced, whereby the signaling-

current is compelled to find its natural circuit through the bridges or branches, and the harmful effect of these is avoided. A switch-board system of this type is illustrated and described in a patent granted to me June 30, 1896, No. 563,073. The line-signal is a small incandescent lamp, which is included in a ground branch containing a battery, together with an impedance-coil or inductive resistance. The usual plug-circuits for making connections between different lines by means of their spring-jacks are furnished, and other signal-lamps are associated with terminal plugs of the plug-circuit, one signal-lamp for each plug. In this system the greatest economy of operation of the signals is attained only by the use of low-resistance impedance-coils in the bridges or ground branches containing the lamp-signals and of high-resistance signal-bells at the substations. Hence the difficulty which I have mentioned becomes important, and the application of my present invention is of peculiar advantage. In combining these two devices I may use the secondary helix of the induction-coil of my present invention as the impedance-coil of my earlier invention. I include the primary helix of the same induction-coil in a local circuit, including a generator of signaling-current, which is normally interrupted at two points—namely, between registering contact-pieces of the spring-jacks and of the terminal plugs of the plug-circuits and between the switch-contacts of a calling-key in the plug-circuit. This latter key is constructed to interrupt the plug-circuit also during the transmission of a signal, so that the signaling-current is not diverted through the plug-circuit to produce false signals in the call-initiating line.

The accompanying diagram shows the circuits of my present invention in combination with those of my earlier application referred to. Two substations A and B are represented, connected by line-wires, with switching and signaling apparatus at the central station C. At the substation a receiving-telephone *a* and a transmitting-telephone *a'* are included serially in one branch from the line conductor

1 and a signal-bell α^2 in another branch from the same conductor. The lever of the telephone switch-hook α^3 constitutes a circuit-terminal of the line conductor 2 and serves to 5 switch the telephonic and the signaling appliances alternately into the line. The receiving-telephone α may be of twenty-five ohms resistance, and the transmitting-telephone may have a normal quiescent resistance of one hundred 10 or two hundred ohms. The bell α^2 should have a high resistance, five thousand ohms being a suitable amount. The line conductor 1 extends to two spring-jacks b and b' on two different sections c and c' of a multiple switch-board. It is continued through a signal-lamp d on section c' , associated with spring-jack b' , and through the helix e^2 of the transformer e and thence to earth through a battery f , which may be common to the different lines of the 15 exchange. Line conductor 2 is connected with other contact-points in the same spring-jacks and is led through an impedance-coil g to earth. Battery f is thus in a bridge of the telephone-line, said bridge including the signal-lamp d and helix e^2 of the transformer on one side of the battery and the impedance-coil g on the other side thereof. The coil g and the helix e^2 may have approximately equal 20 resistances and impedances for the purpose of 25 maintaining the static balance of the line-circuits as to telephonic currents. Battery f should be of such electromotive force that the normal current flowing out through conductor 1, bell α^2 , at the substation and returning 30 through line 2 shall be insufficient to illuminate the lamp d . When, however, the circuit is completed at the substation through the telephones, the high resistance of the bell α^2 will be cut out of the circuit and the lamp d will 35 be lighted. On each spring-jack of the line is 40 a tubular thimble h , which is presented at the front of the spring-jack in order that it may serve as a test-ring. The different rings h are 45 connected with wire 3, which includes the primary helix e' of transformer e and extends to one pole of the generator i of signaling-current. The usual plug-circuit formed by link conductors 4 and 5, terminating in loop-plugs k and k' , is provided for switching the lines into 50 connection with each other by means of their spring-jacks. Three contact-pieces (designated l , l' , and l'' , respectively) of the plug register with the two line-springs and with the test-ring h of a spring-jack into which the 55 plug is inserted. Contacts l and l' of the plugs k and k' form the terminals of the conductors 4 and 5 of the plug-circuit, respectively. The conductor 4 includes serially two helices of the transformer m and is grounded at a point intermediate of the helices. The other conductor 5 of the plug-circuit includes serially the other two windings of the transformer or induction-coil and also includes the supervisory signal-lamps n n' , said lamps being 60 interposed serially in said conductor between the

two last-mentioned windings of the induction-coil. The free pole of the battery f is connected with said conductor at a point between the two supervisory signal-lamps n n' , and so between the two windings of that half of the induction-coil which is serially included in the conductor 5. Signal-lamps n and n' are shunted by resistance-coils o and o' and a battery p . This last device forms an important feature of my Patent No. 563,073, 70 referred to, and is fully described in the specification. I may mention here, however, that battery p is of such strength as to illuminate lamps n and n' through their resistances o and o' while the plug-circuit is incomplete; but it is so adjusted with respect to battery f that when this circuit is completed by the removal of the substation-telephone of a line with which the plug-circuit may be connected the current of battery p is diverted from lamps n 75 and n' , leaving them dark. Hence either of these lamps becomes lighted or dark as the telephone of the line with which the corresponding plug k or k' may be connected is removed from or replaced upon its switch-hook. 80 The lamps thus serve to indicate the condition of use or disuse of the apparatus at the different stations of two connected lines. 85

The operator is furnished with the usual telephone set q and key r for controlling its 90 connection with the cord-circuit 45. The center of the magnet-coil of the receiving-telephone is grounded for testing purposes in the usual way. In each plug-circuit is a calling-key s for transmitting a signaling-current 95 through plug k' to the substation of the line with which this plug is connected to operate the bell α^2 there. This key has three switch-springs s^1 , s^2 , and s^3 , each having a normal resting contact. The conductors 4, 5, and 6 100 include the resting anvils and switch-springs of this key in the order named. When the key is manipulated, the switch-springs are separated from their anvils, the conductors 4, 5, and 6 being thereby interrupted, and the spring s^3 is closed to its alternate contact-point s^4 , which constitutes a terminal of generator i of signaling-current. 105

The mode of operation of the line-signals d and the supervisory signals n and n' preliminary to and during the existence of connection between lines has, I believe, been sufficiently described. I will therefore pass to that stage of the process of connecting-lines which involves my present invention—that is, when having answered the call from line at station A, for example, the operator inserts plug k' into the spring-jack b^2 of line to station B to transmit a signaling-current to the bell at that station. The depression or manipulation of key s interrupts the connection of plug k' with the remainder of the plug-circuit and closes the contact-piece l' , which now registers with the ring h of the spring-jack b^2 against the anvil s^4 . A local circuit from 110 115 120 125 130

generator i is thus completed through conductor 7, a portion of conductor 6 to the contact-piece l^2 , thence through wire 3 and primary helix e' of transformer e . The alternating current created by the generator in this circuit induces in the coil e^2 a corresponding alternating current which finds a path through conductors 8 and 9 to station B and there through the bell a^2 ringing the bell and giving the signal. It will be observed that this current finds circuit serially through the ground branches at the central station instead of being shunted from the line-circuit, as in the system commonly employed.

For the purpose of producing a suitable "busy test" for the multiple switchboard I have made use of conductor 6 and test-rings h , with their associated circuits. A grounded battery t is connected with conductor 6, so that from the moment a plug is inserted into any spring-jack of a line the test-rings h of the line are electrified to a difference of potential from earth. The operator requiring information as to the condition of the line may test in the usual way by applying the tip l of the plug h' to the test-ring of the spring-jack, when, if the line be in use, a current will be produced through conductor 5, key r and one-half of the magnet-coil of the receiving-telephone to earth. An audible signal will then be caused in the telephone, which will indicate that the line is already in use.

My invention is defined in the following claims:

1. The combination with two telephone-lines and link conductors 4 5 at a central office, and connection-switches $h h'$ of said link conductors, for temporarily uniting said lines in a complete telephone-circuit, the called line having a signal-bell at the substation, of a line-battery, a signal-indicating device, and a normally inactive source e^2 of calling-current adapted to operate the substation call-bell, permanently included in the circuit of the called line independent of the telephonic-circuit established by said link conductors, a local circuit established at the connection-switch of the called line and including a source of current and a device e' , adapted to render said source e^2 of calling-current active, and a calling-key having switch-contacts adapted to break the telephone-circuit between the lines and complete said local circuit, whereby the signal-bell at the called station is rung, substantially as described.

2. The combination with two telephone-lines, each extending from a substation to a central office, one of said lines being a calling-line and the other a called line, of a source of

current, a line-signal and the secondary of an induction-coil permanently included in the circuit of each line at the central office, link conductors 4 5, and connection-switches $h h'$ for uniting the lines at points between the induction-coil windings thereof and the respective substations, forming a through-circuit for telephonic communication between the substations, a signal-bell at the substation of the called line, a local circuit established at the connection-switch of the called line including a calling-generator and the primary of the induction-coil of that line, and a calling-key having contacts adapted to break the circuit of the link conductors and close said local circuit, whereby the signal-bell at the called station is operated, as set forth.

3. The combination with a telephone-line extending from a substation to a central office and a substation-switch controlling the circuit of said line, of a call-bell at the substation, two branches for the line at the central office, one of said branches being permanently connected with the line, a secondary source of ringing-current included serially therein, together with a battery and a line-signal, a switch for making connection with the line through the other of said branches, said last-mentioned branch forming a portion of the talking-circuit of said line, a normally open local circuit containing means for rendering said secondary source of current active, and a key adapted when actuated to open said talking-circuit and close said local circuit.

4. The combination with a telephone-line extending from a substation to a line-signal and a battery at the central office, of a substation-switch controlling the circuit of said line, a signal-bell at the substation, a secondary source of ringing-current permanently included in the line at the central office, a branch circuit adapted when completed to form a continuation of the telephonic circuit of said line, a connection-switch adapted to connect said branch with the line at a point between the said secondary source of ringing-current and the substation, a local circuit partially established by the closure of said connection-switch, including means for rendering said secondary source of current active, and a key adapted when actuated to open said branch circuit and complete said local circuit.

In witness whereof I hereunto subscribe my name this 12th day of July, A. D. 1895.

CHARLES E. SCRIBNER.
